COMBINATION TANK AND PACKAGE DELIVERY BODY

Edward H. Gill, Kansas City, Mo., assignor to
Andrew A. Kramer, Kansas City, Mo.

Application May 1, 1936, Serial No. 77,378

17 Claims. (Cl. 280—5)

My invention relates to a combination tank and package delivery body, and more particularly to a combination body comprising a lower tank portion and an upper open body portion that can be used for hauling loose material, packages, or anything else that can be hauled in an open, or express type body.

It is a purpose of my invention to provide a combination body for vehicles of the above mentioned character, which is of light weight for the amount of load adapted to be carried thereby, which has a good appearance and which has a low center of gravity and a low loading edge for a combination body of this character.

It is a particular purpose of my invention to provide a combination body of the above mentioned character that is made up of a lower tank portion and an upper open body portion in which the bottom of the open body portion and the top wall of the tank portion are formed by a wall common to the tank portion and the open body portion, and in which the body is provided with a skirting that encloses the tank portion of the combination body and is so arranged that it gives the vehicle a good appearance, in conjunction with the side and end walls of the open body portion.

It is an important purpose of my invention to provide the top of the tank portion with means for stiffening the same, and for increasing the capacity of said tank portion. To accomplish this the tank top wall inclines downwardly slightly from the longitudinal center line thereof toward the side walls of the tank, and is provided with V-shaped stiffening formations running lengthwise thereof.

It is another purpose of my invention to provide a combination body of the above mentioned character, in which the bottom or bed portion of the open body portion is supported by means of the supporting means for the tank portion directly on the vehicle frame instead of through the tank portion as a whole, said supporting means for the tank portion comprising transverse walls that extend beyond the tank portion and define the compartments of the tank portion, said transverse walls comprising partitions and end walls, or heads of the tank portion.

It is a further purpose of my invention to provide compartments within the skirting at both sides of the vehicle and at the rear of the vehicle so that any suitable receptacles or apparatus may be stored in said compartments and so that the valves, or faucets for withdrawing the liquid from the vehicle, may be housed within said skirting,

the valve compartment being, preferably, obtained by extending the open body portion beyond the tank portion and providing a skirting enclosing a space under the open body portion endwise beyond the tank portion.

It is another purpose of my invention to provide filling means for the tank, so arranged adjacent the side walls of the open body as to leave as much clear space as possible in the open body portion and to provide said open body portion with suitable drainage means, with suitable venting means and with suitable means for dividing the load in said open body portion, should this be desired.

It is an important object of my invention to provide a combination body of the above mentioned character that is so constructed that the skirtings referred to can be mounted on the said body in such a manner that relatively light gauge material can be used without said skirtings becoming warped, or bent, in fabrication or in use.

Other objects and advantages of my invention will appear as the description of the drawings proceeds. I desire to have it understood, however, that I do not intend to limit myself to the particular details shown or described, except as defined in the claims.

In the drawings:

Fig. 1 is a side elevation of my improved vehicle body applied to a truck, the forward portion of which is broken away.

Fig. 2 is a top plan view of my improved vehicle body.

Fig. 3 is a rear elevation thereof.

Fig. 4 is a longitudinal sectional view through said body mounted on a vehicle frame, the forward end of the vehicle frame being broken away.

Fig. 5 is a section taken on the line 5—5 of Fig. 4.

Fig. 6 is a fragmentary longitudinal sectional view, on a larger scale than Figs. 4 and 5.

Fig. 7 is a section taken substantially on the line 7—7 of Fig. 6.

Fig. 8 is a fragmentary longitudinal sectional view, similar to Fig. 6.

Fig. 9 is a transverse sectional view taken on the line 9—9 of Fig. 4.

Fig. 10 is a section taken on the line 10—10 of Fig. 5 on an enlarged scale, the bottom of the compartment being omitted.

Fig. 11 is a fragmentary horizontal section taken substantially on the line 11—11 of Fig. 3, showing the mounting for the removable endgate section.

Fig. 12 is a fragmentary horizontal sectional view

view through a portion of the end wall of the open body portion of my combination body and the adjacent endgate member taken on the line 12—12 of Fig. 3.

5 Fig. 13 is a fragmentary transverse vertical section of a modification.

Fig. 14 is a section taken on the line 14—14 of Fig. 13 on an enlarged scale, and

10 Fig. 15 is a fragmentary sectional view of the venting means shown in Fig. 13 on an enlarged scale.

Referring in detail to the drawings, my combination vehicle body comprises an open upper body portion 20 and a lower tank portion 21, said open body portion 20 being of somewhat greater extent in length than the tank portion 21 so as to provide a space at 22 under the open body portion 20 beyond the rear end of the tank portion 21. The combination body is shown as being mounted on a vehicle having longitudinal frame members 23, upon which sills 24 may be mounted for supporting the tank body over the rear wheels 25 and rear axle 26.

At the forward end of said body a pivotal mounting for the body on the vehicle frame is provided, said pivotal mounting comprising a bottom plate 27, which is secured to the longitudinal frame members 23 by means of bolts 28, and which has an upwardly extending flange, or fin, 29, which has an opening therein for a pivot 30 that extends longitudinally of the vehicle and of the combination body. The pivot member 30 is also mounted in an opening in a curved plate 31, which is welded to a pair of tubular members, or pipes, 32. The pipes 32 are welded in extensions 33 of the transverse walls 34 provided in the tank portion 21 to serve as partitions and as end walls for the tank body and divide the same into a plurality of compartments. Said pipes 32 may be, and preferably are, a pair of the outlet pipes of the compartments of the tank body portion and are extended forwardly beyond the compartments, which the same drain, so as to extend to the forward transverse wall 34, which serves as the front head of the tank and are welded shut at the forward ends thereof so that no liquid draining from the tank can possibly escape therefrom. The pivotal mounting at the forward end of the tank is further provided with headed rod-like members, or bolt-like members 35, which are secured to the member 27 and which extend through openings in a flange 38 on the extension 33 and have compression springs 39 mounted between the heads on the members 35 and the flange 38, thus providing a yielding, rocking mounting of the body at the forward end thereof on the vehicle frame.

The transverse walls 34 are, preferably, made substantially identical in shape and comprise the downward extensions 33, which have been previously mentioned, having the flanges 38 thereon extending transversely thereof at the bottom edges of said extensions and resting on the sills 24 where said sills underlie said tank body portion. Of course, the location of the transverse walls 34, except for the end walls forming the heads of the tank, will vary in accordance with the capacity desired for the compartments of the tank body.

70 Flanges 40 are also provided on the extensions 33 and said transverse walls 34 also extend beyond the tank shell portion of the tank body to provide inclined fins 41 lying on opposite sides of the extensions 33 and extending the greater portion 75 of the distance to the sides of the tank por-

tion of said vehicle. Angles 43 extend between the fins 41 and are welded thereto, said angles running lengthwise of the combination body exteriorly of the tank portion and within the skirtинг provided on the combination body.

5 The shell of the tank portion of the combination body comprises a curved bottom portion 44, which merges with a substantially vertical side wall 45 at each side of the shell, and a top wall 46, which is secured to the side wall portion, by 10 welding, along the upper side corners of the tank portion of said body. Said top wall 46 is nearly flat, but inclines slightly downwardly from the longitudinal center thereof, to the side walls, the highest point thereof being indicated by the 15 numeral 42. In order to provide strength and stiffness for said top wall 46, it is not only inclined, but is provided with V-shaped reinforcing ribs 18 running lengthwise thereof and having flanges 19 thereon welded to the inner face 20 of said wall 46. In order to obtain a strong welded joint, the side wall portions 45 of the shell are flanged inwardly at 47 and are welded to the inner face of the top wall 46 at 48, and to the longitudinal edge of the top wall 46 at 25 49. The shell is, of course, made in sections and the welds between the transverse wall portions 34 and the curved bottom portions and side wall portions of the shell are made on the exterior of the shell, as indicated at 50. The joints in the 30 top wall 46 of the tank shell are made so that the same overlie the flanges 51 provided on the transverse walls 34, the sections of the top wall being welded at 52 and 53 to said wall 34 and the flange 51, and a weld is further provided at 35 54 between the abutting ends of the top wall sections 46. It is, of course, to be understood that the top wall 46 also serves as the bed, or bottom, of the upper body portion of the combination tank body and the top surface thereof is, preferably, roughened in any desired manner 40 to provide a non-skid surface for said bed of said open body portion.

It will be noted that by means of the transverse wall portions 34 and their extensions 33 45 the tank body portion, as well as the open body portion, are supported directly on the vehicle frame through the sills 24 and the pivotal support at the forward end of the body. Thus any weight that may be supported by the bed 46, 50 constituting the top wall of the tank body portion, will be supported by means of the partitions and end walls 34 of the tank, and not by means of the shell portion of the tank along the side and bottom walls thereof. The pipes, or 55 tubular members, 32 serve as longitudinal bracing means to transfer the load from one extension 33 of a transverse wall 34 to the next extension 33 thereof, and so on, to a supported one of said extensions. Further bracing the tank 60 body and connecting said extensions is a hose tube 55, which is welded in the extensions 33 and extends from the forward transverse wall portion 34, or forward head, of the tank body portion to the rear transverse wall portion 34, or 65 rear head, of the tank body portion, and extends into the space 22 located under the open body portion rearwardly of the rear end of the tank portion.

It will be noted that the tank portion of the 70 vehicle is of a substantially semi-rectangular and semi-elliptical cross section, the lower portion thereof being semi-elliptical, thus giving greater strength to the tank body where the major portion of the weight of the liquid would be applied 75

to the shell, and due to the fact that the major axis running transversely of the tank body is much greater than the minor axis thereof running vertically of the tank body, a tank body of 5 large capacity and low center of gravity is obtained, which underlies the open body portion of the combination body. It will be noted that the reinforcing members 18 have the ends thereof spaced from the transverse walls 34 and the 10 flanges 51 thereon, to prevent pocketing of liquid in the V-shaped members.

Sump outlets 59 are provided for the compartments of the tank body leading to the pipe lines 32, previously mentioned. Said pipe lines extend 15 into the space 22 and are each provided with a gate valve 60, which is adapted to connect the pipe line with a manifold 61, which may be provided with any suitable faucet, or other means for withdrawing liquid therefrom. It is obvious 20 that any other valve arrangement than that mentioned could be provided, but the valves, or faucets, that are provided are to be located in the space 22. Said space 22 is further provided with a shelf 62 therein through which the stems 25 of the valves 60 may extend, said shelf being supported in any desired manner on the rear transverse wall portion 34 and the skirting, which is to be described below, such as by the angles 63 shown in Figs. 3 and 4.

30 The combination tank top wall and bed 46 has secured thereto along the margins thereof, the angle members 65, which project slightly beyond the margins of the wall 46 and are secured thereto by the welds 49 and 66. The angles 65 extend 35 slightly beyond the margins of the horizontal wall 46 so that the skirting 67 can be secured flat against the upwardly extending leg of the angle 65 and will clear the projecting welds 49. The skirting members 67 are secured to said upwardly 40 extending legs of the angles by the bolts 68, or similar fastening members. Of course, these could be welded if desired, but, preferably, a light gauge metal is used for the skirting member 67, which might tend to get warped out of shape in 45 welding the same, and it is accordingly preferred that some cold method of securement, such as riveting, or bolting, be utilized for connecting the upper edge of the skirting 67 to the angle member 65. The skirting 67 extends on both sides of 50 the combination body and also around the rear thereof to enclose all of the space under the open body portion, or specifically, under the wall 46.

Inasmuch as the combination body extends a considerable distance sidewise beyond the longitudinal frame members 23, spaces are provided 55 between the skirting member 67 and the tank body portion 21 and longitudinal members of the vehicle frame. These spaces are, preferably, utilized for suitable storage compartments, which 60 may be mounted in any desired manner, but are, preferably, mounted in such a manner that the storage compartments, or other compartments provided in said spaces, are supported from the transverse wall portions 34, which act as supporting members for the combination body, and from the flanges 40 on the extensions 33, and further serve as bracing means for the skirting 67 to hold the same in its proper vertical position.

Said compartments, preferably, comprise a 70 rear wall 68, which may be secured by headed securing members 69 to the flange 40, side walls 70, which are secured by means of headed securing members, such as the bolts 71, to the fins, or flanges, 41 projecting from the tank body and being extensions of the transverse walls 34, and

a bottom wall 72 integral with said side walls; upon which a wooden bottom 73 is mounted. The skirting 67 is braced by means of the walls 70 of the compartments, by securing said skirting to the side walls 70 as said walls 70 extend between 5 said skirting and the transverse walls 34. The skirting 67 is flanged in at 74 and the side walls 70 are secured to said flanges 74 by means of bolt-like members 75. Any arrangement and size of storage compartments may be provided, 10 but it is, of course, desirable to utilize all the available space within the skirting for storage purposes for receptacles, or other apparatus that it may be desired to carry on the vehicle. Further bracing the skirting 67 lengthwise at a point 15 spaced between the top and bottom edges thereof, is the angle member 43, which is secured to the skirting by any suitable means such as counter-sunk rivets.

Any suitable arrangement of doors may be 20 provided on the compartments that are provided within the skirting, such as the single door 71 for a small compartment, and paired doors 78, which may be made of hinged sections so that the same may fold upon each other, the hinges being 25 indicated at 79 and being, preferably, what is known as a piano hinge. The doors are provided with flanges 76 along the edges thereof having the inturned flanges 77 thereon. At said storage compartments the Z-bar 43' is provided 30 instead of the angle 43 acting as a stop for the door. Said Z-bar is welded to the fins 41 and bolted to the skirting 67 by the counter-sunk bolts 16.

The skirting is, of course, cut out to accommodate the wheels 25 and may be provided with a beading 80 extending along the entire bottom edge of the skirting, including the curved cut outs at said wheels. An angle 125 is also secured along the lower margin of said skirting on the inner 40 face thereof to stiffen the same.

The rear portion of the skirting 67 is shown as being provided with paired doors 78, similar to the doors previously described, giving access to the space 22 back of the rear transverse wall 34 45 on the tank portion of the body and below the wall 46 forming the bottom wall of the upper open body portion 20 of the combination body. It will be obvious that when the doors 78 in the rear skirting portion 67 are opened, access can be had 50 to the shelf 62, to the hose tube 55 and to the valves, or faucets, that may be provided in the compartment or space 22. The shelf 62 can be utilized for placing any suitable receptacles thereon, or for any other purpose desired. 55

The angle members 65 also serve to support the bottom edges of the side wall 81 of the open body portion and of the front end wall 82, which is similar to the wall 81, and the rear end wall portions 83, which are fixed and which lie on opposite sides of the removable end wall portions, or endgate members 84. The bottom edges of the vertical wall portions 81, 82 and 83 are secured in the same manner to the angle member 65. This is, preferably, done by means of the headed 60 securing members in the form of bolts 85. In order to hide the joint between the vertical walls 81 and 83 and the skirtings 67 and the bolts for securing said skirtings 67 and said vertical wall portions to the angles 65, a curved bead member 65 for covering the joint is provided, which is secured to the angle members 65 by means of the counter-sunk rivet members 87.

The vertical walls 81, 82 and 83 are further supported and braced by means of the vertical 75

angle members 88, which are welded to the angle members 65, being cut out suitably so that one leg of each angle 88 and of each angle 65 lies flush against the wall 81, 82 or 83, as the case may be, after the same have been secured together, 5 gusset plates 89 being provided between the angle members 65 and 88, said gusset plates being welded to both the angles 65 and 88. Similar gusset plates 89 are provided between the vertical 10 angle members 88 and the top longitudinal angle member 90 extending along the top of the vertical walls 81, 82 and 83 to brace the top vertical edges thereof, said vertically extending angle members 88 being also suitably cut out at the 15 top ends thereof along one flange of the same to place said flange flush with the corresponding flange of the horizontally extending angle member 90 so that the vertical wall portion associated therewith will engage said flanges flatly. 20 The vertical walls 81, 82 and 83 have horizontal flanges 91 extending along the horizontal leg of the angle 90 and depending flanges 92 covering the angle members, the bottom edges of said depending flanges 92 being doubled back at 93 25 to provide a smooth edge along said bottom edge of said flange. The vertical wall portions 81, 82 and 83 are secured to the angle members 90 by means of bolts 94 extending through the vertical legs of the angles 90. A curved bead 95 is 30 provided to finish the top edge of the vertical wall portions 81, 82 and 83 and cover the bolts securing the vertical walls to the angle members 90, said curved bead members 95 being secured in position by means of counter-sunk rivets 96, 35 which connect the same with the vertical legs of the angles 90.

The detachably mounted rear wall portions 84 are constructed in a similar manner to the wall portion 81, but are made in two removable sections, each of which has a pair of depending post-like members 97 secured thereto, which are 40 adapted to enter the rectangular socket members 98, which are secured by welding, or in any other suitable manner, to the rear transversely 45 extending portion of the skirting 67, said sockets 98 being of suitable length that the sections 84 will be supported in vertical position and in alignment with the wall portions 83 adjacent thereto. A roughened corner plate 99 may be 50 provided at the rear end of the open body portion in alignment with the opening provided when the members 84 are removed, so as to protect the top edge of the skirting 67. This is preferably a downturned flange on the wall 46. 55 The tank compartments are each provided with an upstanding tubular filler member 100, which lies closely adjacent one of the side walls 81 and which is provided with a dome-like end portion 101 at the upper end thereof, which is 60 provided with a suitable fill collar having a closure member 102 associated therewith, which may be of any suitable form, but is shown as being of the lever type for quick opening convenience. Vent members 103 are provided extending up- 65 wardly from the compartments through the wall 46 adjacent the opposite wall from that having the filler members 100 located adjacent the same. The vent members 103 comprise upstanding tubular members having elbows 104 thereon, which 70 are connected with suitable elbows 105 to provide a depending connection for a coupling 106, which is adapted to screw-threadedly receive a valve casing 107 in which a ball check valve 108 is mounted. Said vent members serve to prevent 75 the formation of a vacuum in the tank when

liquid is being withdrawn therefrom through any one of the outlet pipes 32.

Paired angle members 109 are also provided along the side walls 81 in oppositely arranged pairs, said members 109 being welded to the horizontal leg of the angle 65 and are so spaced that a transverse bar, such as shown at 110, may be placed between the same to prevent shifting of the load along the bottom 46, said member 110 serving as a load separating member, it being obvious that as many of the members 110 can be provided between the paired members 109 located along the side walls 81 as may be found necessary for preventing shifting of the load carried in the open body portion. 15

Means is provided for draining the open upper body portion, drainage openings being provided at 112 in the bottom wall 46. Drain pipes 113 extend from the drainage openings 112 down to the bottom edge of the skirting 67. The drain 20 pipes 113 at the forward end of the vehicle extend through the tank portion, being welded liquid-tight therein, while those at the rear end of the vehicle extend down into the space 22 and well below the shelf 62. 25

The members 97 are secured to the endgate members 84 by suitable securing elements 116 and the ends of the wall portions 83 and of the endgate members 84 are provided with angles 88 for stiffening the same, and also are formed 30 around the angles in a similar manner to the top edges of the wall portions 81, 82 and 83, having flanges 117 extending around the angles 88 along one of the legs thereof, and end flanges 118 extending away from each other having the doubled 35 back portions 119 thereon to provide smooth edges along the margins of said flanges. A rub rail 111 is provided along the inner faces of the upstanding walls of the upper body portion and endgate members, being secured to the angles 40 88 by securing elements 114.

Instead of providing the venting means 103, it is desirable in a body having the sloping top wall 46 for the tank portion thereof, to provide venting means at the highest point in said top wall, 45 or at the ridge formed at 42 where the two side-wise sloping portions of the top wall meet. Venting means of a suitable character for venting the tank portion at the center thereof is shown in Figs. 13, 14 and 15, said venting means comprising a tubular member 126, which is provided with a split, or slot, at 127 and which extends from the bottom wall 44 to the top wall 46 of the tank, being provided with a flanged member 128 at its upper end, which member is welded at 129 in the 55 top wall 46 of the tank. Said member 126 may also be welded to the inner face of the bottom wall 44 of the tank. It is arranged in a vertical direction and serves not only as a vent tube, but also has a guide tube for a measuring stick, or 60 similar member, which may be inserted for the purpose of measuring the quantity of liquid in the tank, preventing the measuring stick from being inserted at an oblique angle, whereby inaccurate measurement of the liquid level would 65 be prevented. This is particularly important in a tank of relatively small depth and great width, such as that shown in the drawings. The flanged member 128 is provided with a shoulder 130 and with internal threads 131, with which a plug 70 132 screw-threadedly engages, said plug having a polygonal opening 133 in the top thereof for engagement by a wrench, whereby the same may be unscrewed for venting the tank or for measuring the contents of the tank, and screwed down 75

into position to provide a liquid-tight closure for said combined vent tube and guide member. It is, of course, to be understood that each compartment of the tank is provided with one of the vent members 126. A movable bumper 56 is provided at the rear end of the vehicle.

What I claim is:

1. A combination body of the character described comprising a lower tank portion having a wide substantially flat top wall, an upper body portion overlying said tank portion, transverse partition means dividing said tank portion into a plurality of compartments, and venting means for said tank compartments each comprising a tubular member extending from bottom to top of said tank portion and open from top to bottom thereof to the compartment in which it is located, and having a closure at the upper end thereof removable to provide an opening from said tubular member to the outer air.

2. A combination body of the character described comprising a lower tank portion, an upper open body portion extending endwise beyond said tank portion, and a housing enclosing the space under said open body portion lying endwise beyond said tank portion, and valves within said housing, said housing having a movable closure providing access to said enclosed space.

3. A combination body of the character described comprising a lower tank portion, an upper open body portion extending endwise beyond said tank portion, and a housing enclosing the space under said open body portion lying endwise beyond said tank portion, and a hose tube running lengthwise of said tank portion and opening into the space enclosed by said housing, said housing having a movable closure providing access to said space.

4. A combination body of the character described, comprising a lower tank portion, an upper open body portion having a bed and vertical side and end walls and means for draining said open body portion at each end thereof, comprising depending drain conduits extending through said tank portion.

5. A combination body of the character described comprising a lower tank portion, and an upper open body portion, said tank portion having a plane faced top wall constituting the load supporting bottom for said upper open body portion, and V-shaped longitudinal reinforcing members on the under face of said top wall open at the ends thereof.

6. The combination with a vehicle frame of a combination body comprising a lower tank portion and an upper freight carrying portion, said freight carrying portion comprising a load supporting bed forming the top wall of said tank portion and said tank portion comprising vertically extending transverse walls extending from said load supporting bed to said vehicle frame and defining compartments in said tank portion, said tank portion having a transversely curved bottom wall and substantially vertically extending side walls connecting said bottom wall with said load supporting top wall and integrally united therewith and with said transverse walls, external longitudinally extending bracing means under said curved bottom wall connecting said transverse walls and internal longitudinal bracing means on said top wall.

7. The combination with a vehicle frame of a combination body comprising a lower tank portion and an upper freight carrying portion, said freight carrying portion comprising a load sup-

porting bed forming the top wall of said tank portion and said tank portion comprising vertically extending transverse walls extending from said load supporting bed to said vehicle frame and defining compartments in said tank portion, 5 said tank portion having a transversely curved bottom wall and substantially vertically extending side walls connecting said bottom wall with said load supporting top wall and integrally united therewith and with said transverse walls, 10 said top wall comprising substantially plane faced portions and said wall being provided with substantially V-shaped longitudinal bracing means integral therewith on the under side thereof lying internally of said tank body. 15

8. The combination with a vehicle frame of a combination body comprising a lower tank portion and an upper freight carrying portion, said freight carrying portion comprising a load supporting bed forming the top wall of said tank 20 portion and said tank portion comprising vertically extending transverse walls extending from said load supporting bed to said vehicle frame and defining compartments in said tank portion, said tank portion having a transversely curved bottom 25 wall and substantially vertically extending side walls connecting said bottom wall with said load supporting top wall and integrally united therewith and with said transverse walls, said top wall comprising substantially plane faced portions and 30 said wall being provided with substantially V-shaped longitudinal bracing means integral therewith on the under side thereof lying internally of said tank body, said V-shaped bracing means being open at the ends thereof. 35

9. A combination body of the character described, comprising a lower tank portion divided into compartments and an upper body portion overlying said lower tank portion, the top wall of said tank portion constituting the load supporting 40 bed for said upper body portion, said top wall comprising substantially plane portions inclining transversely from a high point to the opposite side edges thereof, and venting means for each of said tank compartments comprising a vent tube extending from the bottom of said tank portion 45 through said top wall at said high point.

10. A combination body of the character described, comprising a lower tank portion and an upper body portion, said lower tank portion having a top load supporting wall, said upper body portion comprising vertical walls extending upwardly from said load supporting wall, and means for mounting said vertical walls on said load supporting wall comprising angles integrally united 50 with said load supporting wall and having leg portions to which said vertical walls are secured. 55

11. A combination body of the character described, comprising a lower tank portion and an upper body portion, said lower tank portion having a top load supporting wall, a bottom wall and side walls terminating in inwardly directed flanges underlying and welded to said top wall, said upper body portion comprising vertical walls extending upwardly from said load supporting 60 wall, and means for mounting said vertical walls on said load supporting wall comprising angles integrally united with said load supporting wall substantially at the junction of said side walls therewith and having leg portions to which said 65 vertical walls are secured. 70

12. A combination body of the character described comprising a lower tank portion, an upper body portion extending endwise beyond said tank portion, and a housing enclosing the space under 75

- said upper body portion lying endwise beyond said tank portion, and valves within said housing, said housing having a movable closure providing access to said enclosed space.
- 5 13. A combination body of the character described comprising a lower tank portion, an upper body portion extending endwise beyond said tank portion, and a housing enclosing the space under said upper body portion lying endwise beyond said tank portion, said housing having a movable closure providing access to said enclosed space, and means for draining said upper body portion extending through said housing.
- 10 14. A combination body of the character described comprising a lower tank portion, a freight body portion overlying said tank portion having vertical side walls and a bed, transverse partition means dividing said tank portion into a plurality of compartments, filler members for said tank compartments projecting upwardly from said bed adjacent one of said side walls, and venting means for said compartments projecting upwardly from said bed adjacent the other of said side walls, said filler members and venting means being within the confines of said freight body portion.
- 15 15. A combination body of the character described, comprising a lower tank portion divided into compartments and an upper body portion overlying said lower tank portion, the top wall of said tank portion constituting the load supporting bed for said upper body portion, and venting means for each of said tank compartments comprising a vent tube extending from the bot-
- tom of said tank portion through said top wall, said tube having a slot therein running substantially the full length thereof.
16. A combination body of the character described, comprising a lower tank portion having a substantially flat top wall, bottom and side walls, said side walls having vertical portions, an upper body portion overlying said tank portion and having a vertical side wall and a vertical skirting in substantial alignment with the side wall of the upper body portion, supported by and depending from said top wall, extending alongside the vertical portion of said side wall of said tank portion and to below the bottom of said tank portion, and enclosing said entire tank portion.
17. A combination body of the character described, comprising a lower tank portion and an upper freight body portion having side walls extending upwardly from the top of said tank portion, said tank portion having transverse partition means dividing the same into a plurality of compartments, and having a top wall transversely downwardly inclined from substantially the longitudinal center line of said tank to said side walls, filler members for said compartments projecting upwardly a substantial distance from said top wall and lying within the confines of said upper body portion adjacent one of said side walls, and venting means for each of said compartments at the highest point of the top wall thereof.
